UNITED STATES PATENT OFFICE.

ALVAH C. ROEBUCK, OF WOODSTOCK, ILLINOIS, ASSIGNOR TO WOODSTOCK TYPEWRITER COMPANY, OF WOODSTOCK, ILLINOIS, A CORPORATION OF ILLINOIS.

SHIPPING-SUPPORT.

1,266,860.

Specification of Letters Patent. Patented May 21, 1918.

Application filed February 20, 1915. Serial No. 9,506.

To all whom it may concern:

Be it known that I, ALVAH C. ROEBUCK, a citizen of the United States, residing at Woodstock, in the county of McHenry and 5 State of Illinois, have invented certain new and useful Improvements in Shipping-Supports, of which the following is a specification.

This invention relates to supports for 10 holding the movable parts of a typewriter from movement while the typewriter is being bodily moved, and the principal object of the invention is to provide improved simple supports by means of which this object may be attained in an effective and efficient manner.

Other objects will appear hereinafter.

In the drawings, Figure 1 is a side elevation of a typewriter, some parts of which 20 are omitted, to which supports constructed in accordance with the principles of this invention are applied; Fig. 2 is a detail sectional view taken on the line 2—2 of Fig. 1; Fig. 3 is a perspective of one of the plates 25 attachable to the carriage; Fig. 4 is a sectional view showing the bail for preventing the movement of the actuating levers in position in the sub-frame; Fig. 5 is another view of the shipping bail in position, and Fig. 6 30 is a detail showing one end of the bail.

It has been the custom to hold the type bars in position by placing a cushion of old papers or excelsior wrapped in paper on top of the type bars to hold them in place 35 while the machine is in transit and to hold the carriage by tying it in place, or some equally unsatisfactory method. This is liable to leave pieces of paper or excelsior in and about the type bars so that when 40 the machine arrives at its destination it must be thoroughly cleaned before it can be used. The present invention contemplates the use of supports for positively holding the movable parts in position so that there is no 45 danger of the movable parts becoming damaged or broken in transit, and by simply removing the shipping support the machine arrives in perfect condition ready for instant use.

50 In the typewriter frame designated generally by the reference numeral 8 there are ways 9 in which the ways 10 of the typewriter carriage, designated generally by the reference numeral 11, are mounted by means 55 of balls in the ball race formed between the

ways 9 and 10. Mounted in the carriage is a sub-carriage of which the end plate 12 is shown in Fig. 2 from which projects a stop stud 13 oscillatable between adjusting screws 14 on the carriage. Also pivoted to 60 the carriage is an escapement rack 15 which has a rack release lever 16. This rack normally engages with an escape wheel 17 from which it may be disengaged by pressing upon the release lever 16.

65 Any suitable or well known type of escapement mechanism proper may be used and it is unnecessary to show any particular type in connection with the present case, it being sufficient for the purpose of the present invention to say that the escapement mechanism is actuated by the movement of key-levers 18 suitably pivoted in the frame and having an operative connection with actuating or sub-levers 19 mounted in a sub-frame 20 (see Fig. 4) and suitably connected to type bars 21. This is a well known 70 form of typewriter construction and the invention in the present case consists in the application to this construction of suitable 75 means for holding the movable parts from movement while the typewriter is being transported.

80 A pair of end plates, one of which is shown in Fig. 3, is provided for the carriage 85 and each plate 22 consists of a single piece of material with a perforation 23 through which a screw 24 may be inserted for securing the plate to the carriage and with a tapped hole 25 into which the screw can be 90 threaded after removal for preventing the screw from being lost. The plate is also provided with projections 26 and 27, the first of which is adapted to be inserted beneath one end of the rack 15 for raising it 95 and the other projection 27 is adapted to be inserted between the adjusting screws 14 and over the stop stud 13 of the sub-carriage for holding it in fixed position. Two studs 28 are fitted loosely in holes in the plate 22 and 100 these studs are adapted to be inserted in the ends of the ball race to hold the plate in proper position. The studs are provided with nuts 29 which are tightened to hold the studs securely in place after the plate 105 is in position.

110 Unthreaded holes 30 are provided in the ends of the sub-frame 20 (see Fig. 5) which are adapted to receive the unthreaded ends of a bail 31. This bail is preferably con-

structed of steel wire and adjacent each end is formed with a flattened portion 32 to limit the extent to which the ends of the bail may be inserted in the perforations 30. The bail proper is sprung in place in front of the actuating or sub-levers 19 so that the bail proper extends in front of the sub-levers 19, Fig. 4, and effectually prevents their forward movement. By preventing the forward movement, the type bars 21 are also prevented from movement and are held in place on the type bar rest so that there is no tendency for them to become entangled with other type bars and bent, thus throwing them out of alinement.

With this construction it is obvious that the movable parts of the typewriter are securely held and supported so that the typewriter may be shipped without any danger or accident or without any danger that the parts will become damaged in transit. Not only is the carriage held against longitudinal movement but also the sub-carriage is prevented from shifting movement. The escapement mechanism is double protected for the rack is held out of engagement with the escape wheel and there can be no movement of the escape mechanism because the actuating levers for it are held against actuating movement.

To remove the supports it is necessary only to place the fingers through the sides of the frame and lift the ends of the bail 31 upward so that it can be removed from the perforations 30; the end plates 22 are easily removed by simply withdrawing the screw 24 whereupon the plate may be slipped out at the side of the machine, the rack being thereby released and the stud of the sub-carriage being free for shifting movement.

The studs 28 prevent the weight of the carriage from causing the balls in the vacancy to pit the ways of the ball race, in case of a heavy jar or impact while in transportation. The center of the bail 31 is immediately under the lowermost type bar 21, but in inserting or removing the bail will spring sufficiently to permit inserting and withdrawing the ends of the bail.

It is obvious that a strip of metal may be used instead of a wire bail and that the bail may be secured to the sub-frame by means of screws inserted through eyes or perforations in the bail. Other changes may be made without departing from the spirit or scope of the invention.

What I claim is:

1. In a typewriter, a movable carriage and an escapement rack pivoted therein, escapement mechanism to engage the rack, and shipping plates attached to the ends of the carriage and provided with engaging means to hold the carriage against movement and the rack raised from connection with the escapement mechanism.

2. In a typewriter, a movable carriage and an escapement rack pivoted therein, escapement mechanism engaging the rack for moving the carriage, and means including typebars for operating the mechanism; plates attachable to the ends of the carriage with engaging means for holding it against movement and the rack raised from the escapement mechanism; and means for preventing movement of the typebars.

3. In a typewriter, a movable carriage, escapement means for moving the carriage including type bars, a pivoted escapement rack disengageable from the escapement means, means for holding the carriage against movement and the rack out of engagement with said escapement means, a support for the type-bars having a perforation at each end, and a bail with flattened portions adjacent the ends to limit the extent of insertion of the ends of the bail, the bail engaging the typebars for holding them against actuation.

4. The combination of a typewriter having a shiftable carriage with ways upon which the carriage is transversely movable, a shipping support for the carriage consisting of plates, one of which is attachable at each end of the carriage, having projections insertible in the ways thereof and other projections to engage the carriage to hold it against shifting movement.

5. A shipping support for the carriage of a typewriter consisting of a plate attachable to the carriage at one end with projections to engage in the ways upon which the carriage is movable, and with other projections to engage and support the carriage from shifting movement.

6. The combination with a typewriter having a transversely movable and vertically shiftable carriage and a ball race for mounting the carriage and a pivoted rack for engaging the escapement mechanism, of a shipping support for the carriage consisting of plates, one attached at each end of the carriage and consisting of adjustable projections insertible in the ball races, and other projections one of which engages the carriage to prevent its shifting movement and the other of which engages the rack to prevent its movement with the escapement mechanism.

7. The combination with a typewriter having a shiftable carriage with ways upon which the carriage is transversely movable, ball bearings movable in the ways of a shipping support for the carriage consisting of plates, one of which is attachable to each end of the carriage and each plate having projections insertible in the ways to support the carriage and to prevent the weight of it from causing the ball bearing to pit the ways in case of a heavy impact while in transportation.

8. A shipping support for preventing the movement of the type bars of a typewriter comprising a support with perforations at the ends; and a bail with flattened portions adjacent the ends to limit the extent of insertion of the ends of the bail, the bail being adapted to engage below the typebars for holding them upon their seat.

In testimony whereof I have signed my name to this specification, in the presence of 10 two subscribing witnesses, on this eleventh day of February, A. D. 1915.

ALVAH C. ROEBUCK.
